US0D1077043S

(12) **United States Design Patent** (10) **Patent No.:** **US D1,077,043 S**
(45) **Date of Patent:** **** May 27, 2025**

(54) **POINT-OF-SALE TERMINAL**

(71) Applicant: **FUJIAN NEWLAND PAYMENT TECHNOLOGY CO., LTD.**, Fuzhou (CN)

(72) Inventors: **Jujie Zhang**, Fuzhou (CN); **Cuiting Zhong**, Fuzhou (CN); **Xuanqing Chen**, Fuzhou (CN); **Gaoxin Lin**, Fuzhou (CN)

(73) Assignee: **FUJIAN NEWLAND PAYMENT TECHNOLOGY CO., LTD.**, Fuzhou (CN)

(**) Term: **15 Years**

(21) Appl. No.: **29/909,944**

(22) Filed: **Aug. 14, 2023**

(51) LOC (15) Cl. **18-01**

(52) U.S. Cl.

CLAIM

The ornamental design for a point-of-sale terminal as shown and described.

DESCRIPTION

FIG. 1 is a perspective view of a point-of-sale terminal showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the point-of-sale terminal that form no part of the claimed design.

1 Claim, 8 Drawing Sheets
